Cadmore & Co.

UNITED STATES PATENT OFFICE.

JOHN E. W. FOGAL, OF QUINCY, ILLINOIS, ASSIGNOR OF ONE-HALF TO
JOHN C. DUSSAIR AND HENRY B. DINES, OF SAME PLACE.

ELEVATOR-GATE.

SPECIFICATION forming part of Letters Patent No. 619,400, dated February 14, 1899.

Application filed April 27, 1898. Serial No. 673,966. (No model.)

To all whom it may concern:

Be it known that I, JOHN E. W. FOGAL, a citizen of the United States, residing at Quincy, in the county of Adams and State of Illinois, have invented a new and useful Elevator-Gate, of which the following is a specification.

My invention relates to elevators, and particularly to operating mechanism for elevator-gates, and has for its object to provide simple and efficient means adapted to be applied to elevators of any ordinary construction whereby the gates are successively opened and closed as the car approaches and leaves a landing.

Further objects and advantages of this invention will appear in the following description, and the novel features thereof will be particularly pointed out in the appended claims.

In the drawings, Figure 1 is a perspective view of an elevator-gate-operating mechanism constructed in accordance with my invention applied in an operative position to an elevator. Fig. 2 is a perspective view of the friction-bars and support. Fig. 3 is a similar view of the sheave and friction-roller, with the bracket upon which they are mounted. Fig. 4 is a detail sectional view of the means for guiding the friction-bar and adjusting the tension of its actuating-spring. Fig. 5 is a plan view of the means for securing the upper end of the friction-bar support to the car.

Similar numerals of reference indicate corresponding parts in all the figures of the drawings.

In the drawings my improved elevator-gate-operating mechanism is shown applied to a freight-elevator wherein the car is provided with a platform 1, a transverse beam 2, and uprights 3, an elevating-cable 4 being employed, and said car is mounted between guide-beams 5, while access to the car is had between vertical gate-guides 6, between which is mounted to slide a gate 7.

The attachment constituting the gate-operating mechanism includes a support 8, consisting in the construction illustrated of a board or its equivalent secured at its lower end to the car-platform and at its upper end to the beam 2 by means of suitable braces 9

and 10 or the equivalents thereof, and mounted upon this upright support for horizontal yielding movement are upper and lower friction-bars 11 and 12, arranged in parallel positions, respectively, contiguous to the front and rear edges of the support 8, and hence with an interval between the planes of their contiguous faces or edges approximately equal to the diameter of a friction-roller 13, which is mounted in fixed bearings, preferably upon the frame or an attached part of the elevator-shaft. In the construction illustrated the friction-roller 13 has its spindle 14 mounted in bearings in a bracket 15, which is secured to a horizontal bar 16 of the elevator-shaft by means of bolts 16^a or their equivalents engaging horizontal slots 17 in the securing-plate of said bracket, whereby the horizontal position of the friction-roller may be adjusted to suit the positions of the friction-bars. Secured to the spindle of the friction-roller is a sheave 18, to which is attached the lower end of a gate-operating cable 19, forming a connection between said sheave and the gate 7 and extending between said sheave and gate over suitable direction-pulleys 20, 21, and 22, the direction-pulley 20 being located above the sheave 18, the pulley 21 (shown in dotted lines) upon or contiguous to one of the gate guides or uprights 6, and the pulley 22 centrally above the gate.

The lower friction-bar 12 terminates at its upper end in the plane of the lower end of the upper bar 11, and as these bars are spaced apart horizontally to frictionally engage opposite sides of the roller 13 it will be seen that during upward movement of the elevator-car from a point below said roller the contact of the inner edge or operative face of the upper friction-bar will cause rotation of the roller 13 to wind the gate-operating cord 19 upon the sheave 18 and raise the gate, the lower end of the upper friction-bar 11 reaching the plane of the roller 13 simultaneously with the arrangement of the car-platform in the plane of the landing, and that a further upward movement of the elevator-car will cause the lower friction-bar 12 to engage the friction-roller 13, and thus turn the latter in the opposite direction and lower the gate. In the same way the downward movement of

the elevator-car toward a landing will bring the operative face of the lower friction-bar into contact with the friction-roller 13 to turn the sheave, wind the cable 19, and elevate 5 the gate, and that after the car-platform has passed the landing the friction-roller will be turned by the upper friction-bar in the opposite direction to unwind the cable and lower the gate.

10 In order that an even yielding pressure of the friction-bars may be maintained upon the periphery of the friction-roller, they are mounted at their upper and lower ends in angular guide-brackets 23, consisting in the construction illustrated of bars secured at one end to the inner surface of the support 8 and bent to form front arms 24, perpendicular to the plane of said support, and outer arms 25, which are parallel with the support and 15 between which and the plane of the support the friction-bars are mounted to slide. In order to prevent vertical displacement of the friction-bars and limit the inward movements thereof, I employ guide-rods 26, extended through guide-openings 27 in the perpendicular arms 24 of the guide-brackets and threaded or otherwise adjustably secured to the friction-bars, said guide-pins consisting of bolts which are headed, as shown at 28, to 20 bear against the outer surfaces of the arms 24 when the friction-bars are at the limits of their inward movement. Also to insure the proper frictional contact of the operative faces of the friction-bars with the periphery 25 of the friction-roller I employ actuating-springs 29, preferably of the plate type, secured at their centers to the outer or remote edges of the friction-bars and deflected from the bars toward their free ends for contact 30 with fixed objects, such as the guide-brackets. In the construction illustrated tension-screws 30 are threaded in the perpendicular arms 24 of the guide-brackets and bear terminally against the extremities of the actuating-springs, whereby the resistance offered 35 by the springs to the separation of the friction-bars or the movement thereof from their normal positions may be varied, thus adapting the apparatus for use in connection with 40 gates of different weights.

It will be seen that by the use of friction devices consisting of the friction-roller and the yieldingly-supported friction-bars I am enabled to insure the efficient operation of 45 the gate without strain upon the operative parts and without causing undue resistance to the motion of the car, and it will be understood that by employing sheaves of different diameters or friction-rollers of different diameters I am enabled to secure a movement 50 of the gate through any distance to suit the conditions under which the apparatus is used.

It will be understood that various changes in the form, proportion, and the minor details of construction may be resorted to without departing from the spirit or sacrificing any of the advantages of this invention. 65

Having described my invention, what I claim is—

1. A gate-operating apparatus for elevators 70 consisting of a friction-roller mounted upon the frame of the elevator-shaft and operatively connected with an elevator-gate, parallel friction-bars arranged upon opposite sides of said friction-roller for alternate contact with opposite sides thereof, upper and lower parallel-sided guide-brackets for each friction-bar, guide-pins carried by the friction-bars at their extremities and extending through openings in the brackets, and bowed 75 plate-springs arranged at their convex centers in contact with the rear edges of the friction-bars, and disposed terminally in the said guide-brackets contiguous to the said guide-pins, substantially as specified. 85

2. A gate-operating apparatus for elevators consisting of a friction-roller mounted upon the frame of the elevator-shaft and operatively connected with an elevator-gate, parallel friction-bars arranged upon opposite 90 sides of said friction-roller for alternate contact with opposite sides thereof, upper and lower parallel-sided guide-brackets for each friction-bar, guide-pins carried by the friction-bars at their extremities and extending through openings in the brackets, bowed 95 plate-springs arranged at their convex centers in contact with the rear edges of the friction-bars, and disposed terminally in the said guide-brackets contiguous to the said guide-pins, and tension-screws threaded in the 100 brackets and bearing terminally against the extremities of said springs for varying the tension thereof, substantially as specified. 105

3. A gate-operating apparatus for elevators, 105 consisting of yieldingly-supported upper and lower friction-bars, spaced apart horizontally at their operative faces, a supporting-bracket secured to the frame of the elevator-shaft and having a slotted securing-plate for engagement by fastening devices, a friction-roller mounted upon said bracket for alternate contact with the operative faces of said friction-bars, and of a diameter greater than the interval between the planes of the operative 110 faces thereof when the bars are in their normal positions, a sheave fixed to the spindle 115 of the friction-roller, and a flexible connection between said sheave and the elevator-gate, substantially as specified. 120

4. A gate-operating apparatus for elevators, consisting of a friction-roller mounted upon the frame of the elevator-shaft, and operating connections between the same and an elevator-gate, an upright support provided with 125 means for attachment to an elevator-car, pairs of parallel-sided guide-brackets secured to the said support, with their open sides disposed inwardly, toward the friction-roller, twin friction-bars mounted in said guides for horizontal movement toward and from the axis of the friction-roller, and relatively disposed to successively engage said roller at diametrically opposite points during the movement of 130

the elevator-car in opposite directions, and
springs for yieldingly holding said friction-
bars in their normal or initial positions, said
support, with the attached brackets and fric-
tion-bars, being attachable to an elevator-car
in operative relation with the friction-roller,
substantially as specified.

In testimony that I claim the foregoing as
my own I have hereto affixed my signature in
the presence of two witnesses.

JOHN E. W. FOGAL.
